US0D1067943S

(12) **United States Design Patent** (10) Patent No.: **US D1,067,943 S**
(45) Date of Patent: ** Mar. 25, 2025

(54) **DISPLAY SCREEN OR PORTION THEREOF WITH ICON**

(71) Applicant: **Samsung Electronics Co., Ltd.**, Suwon-si (KR)

(72) Inventors: **Soojung Bae**, Suwon-si (KR); **Hyunkyung Song**, Suwon-si (KR); **Harkjoon Kim**, Suwon-si (KR)

(73) Assignee: **SAMSUNG ELECTRONICS CO., LTD.**, Gyeonggi-Do (KR)

(**) Term: **15 Years**

(21) Appl. No.: **29/905,820**

(22) Filed: **Oct. 26, 2023**

(30) **Foreign Application Priority Data**

Apr. 27, 2023 (KR) 30-2023-0016251

(57) **CLAIM**

The ornamental design for a display screen or portion thereof with icon, as shown and described.

DESCRIPTION

FIG. 1 is a front view of a display screen or portion thereof with icon, showing our new design; and,

FIG. 2 is an enlarged view of the icon in FIG. 1.

The outermost perimeter shown as a pair of dashed broken lines in FIG. 1 illustrates a display screen or portion thereof and forms no part of the claimed design. The remaining broken lines in the figures depict portions of the icon that form no part of the claimed design.

1 Claim, 2 Drawing Sheets
